BALANCED DOOR

Martin Esser, Cleveland, Ohio, assignor to John Harsch Bronze Foundry Co., Cleveland, Ohio, a corporation of Ohio

Application September 19, 1935, Serial No. 41,304

8 Claims. (Cl. 20—16)

This invention relates broadly to mountings for doors, casement windows and similar structures, and more specifically to mountings of the type adapted to permit the vertical edges of the door to extend beyond each side of the opening when the door is adjusted in its open position.

One of the objects of the invention is the provision of mechanism to equalize the balance of the door as it is swung into its open position, and to minimize the wind pressure thereon when in its fully opened position.

Another object of the invention is to provide a mounting for pivotally supporting a door intermediate its marginal side edges which facilitates the smooth even movement of the door as it is revolved and transversely adjusted in its open or closed position.

Another object of the invention is the provision of an offset hinge in which the supporting members and operating linkage therefor are concealed when the door is closed, and of an aesthetic appearance.

Other objects more or less ancillary of the foregoing and the manner in which all the various objects are realized will appear in the following description which, considered in connection with the accompanying drawings, sets forth the preferred embodiment of the invention.

Referring to the drawings wherein the preferred embodiment of the invention is illustrated:

Figure 1 is a front elevational view of a door frame and casing illustrating the application of the improved mounting. The central portion of the door as shown herein is broken away in order to illustrate the essential parts of the mounting and the proportions thereof in relation to the door as clearly as possible;

Fig. 2 is a transverse sectional view taken through the door and casing on the plane indicated by the line 2—2 of Fig. 1;

Fig. 3 is a transverse sectional view of the base of the door, the section being taken on a plane indicated by the line 3—3 of Fig. 1. This section illustrates the door mounting and the linkage therefor, the door and certain parts of the linkage are indicated by dotted lines in their actuated position;

Fig. 4 is a vertical sectional view of the mounting supports, the section being taken on the plane indicated by the line 4—4 of Fig. 1;

Fig. 5 is a similar sectional view showing the mounting support and supporting linkage at the base of the door, the section herein being taken on the plane indicated by the line 5—5 of Fig. 1;

Fig. 6 is a section through the base of the door

showing the connecting link and associated mechanism, the section herein being taken on a plane indicated by line 6—6 in Fig. 1;

Fig. 7 is a sectional view showing the structural details of the supporting linkage, the section herein being taken on the line 7—7 of Fig. 1;

Fig. 8 is a detail vertical sectional view through the lower portions of the door, the section being taken on the line 8—8 of Fig. 1;

Fig. 9 is a structural detail view of the supporting linkage in the upper portion of the door, the section being taken on the line 9—9 of Fig. 1; and

Figs. 10 and 11 are sectional views through the upper portion of the door and a fragmentary portion of the door casing.

Referring to Fig. 1, the door 20 is pivotally supported at its top and bottom edges upon the arms 21 and 22, respectively. These arms are affixed upon a bar or stanchion 23 mounted in brackets or bearings 24 and 25 which are supported within the door frame 26 and concealed therein by the casing. The present embodiment is adapted for use with a metallic door and is illustrated as coordinated with a structural steel door frame, the brackets 24 and 25 being secured thereto by screws or rivets 27. It is to be understood, however, that the present invention is adaptable for use with wood or wood and metal structures and that such construction is contemplated herein. The arm 21 is attached to the door through a stud 28 preferably mounted in a plate 29 affixed upon the upper edge of the door intermediate the marginal edges thereof. As illustrated in Fig. 9 the inner end of the arm 21 is formed with an enlarged arcuate boss 30 described from the center of the pivotal connection to present a smooth uninterrupted surface when the arm is swung into door opening position. The inner edge 31 of the boss 30 is shouldered in lineation of the door casing in order to enhance the appearance of the structure when the supporting arm of the door is disposed in closed position. The arm 22 is pivotally mounted on the door, the load or weight thereof being sustained by an anti-friction bearing 32 interposed between the shouldered end portion of a plate 33 mounted on the door and the recessed end 34 of the arm 22. The inner end of the arm is formed with a boss 35 which is of suitable diameter to form a substantial bearing upon the yoked end 36 of the supporting bracket 26. The inner face of the boss 35 is provided with gear teeth 37 intermeshed with a gear toothed quadrant 38 formed in an arm 39 which is pivotally supported in the bracket 36 by a stud 40. The contour of

30

35

40

45

50

55

the outer face ~~4~~ of the arm 39 is also configured in lineation of the door casing in order to attain the symmetry of design and the aesthetic exterior appearance of the door mounting. The arm 39 is formed with a yoke adjacent its outer end to receive the end of a link 42, the pivotal connection therein being effected through a stud 43. The arm of the link 42 terminates in a cleved end which is fulcrumed through a pin 44 upon a boss 45 formed in the lower portion of the door 20.

The outer edge of the door, as illustrated in Figs. 2 and 3, is adapted to swing in the direction indicated by the arrow, the door jams 46 and 47 providing stops for the vertical edges thereof, while the ledges 48 (Fig. 10) and 49 (Fig. 11) form abutting surface in the upper portion of the casing. As will be seen in Fig. 2, the ledge 48 is of reduced transverse section in order to provide clearance for the projecting flange 50 of the door 20 which is seated in the recess 51 in the upper portion of the casing when the door is disposed in its closed position.

Push plates and handles of a suitable type and as indicated by the bracket 52 (Fig. 3) may be provided to accommodate manipulation of the door. A fluid operated or spring door check 53, concealed below the surface of the floor, and operatively connected to the shaft 23 may be provided if desired to snub the movement of the door upon operation thereof. If desired the movement of the door may be snubbed by a spring or other suitable check coordinated with the stanchion 23 built within the door casing.

In operation, when the door is opened the initial movement thereof about the pivots 28 and 32 will cause the link 42 which is fulcrumed forwardly of pivots to overtake the arm 39 and the inter-geared arm 38, which in turn breaks the pivotal connection 43 between the link 42 and arm 39 and causes the door to be rotated as it swings through the opening upon its supporting arms 21 and 22. When the arm 39 is swung substantially 90 degrees and is disposed in its fully retracted position as indicated in the dotted lines 45 in Figure 3, the door will be rotated and drawn laterally until it has reached a position adjacent the frame and substantially normal to the plane of the door in its closed position. As the link 42 is revolved, as shown in dotted line position in Figure 3, to the limit of its extended position, arm 22 will be swung upon its fulcrum 23 to the position indicated by the dotted lines in Figure 3, the portions of the arms effecting a steady uniform translation of the door throughout such 55 operating cycle and at the same time sustaining the balance of the door.

The vertical edges of the door in its open position being disposed beyond each side of the door opening will be equalized, the wind pressure thereon will be realized while the door is swung to its open position, since the lateral edges of the door are rotated upon the supporting arms 21 and 22 and the door is simultaneously guided by the links 39 and 42.

Although the foregoing description is necessarily of a detailed character, in order that the invention may be completely set forth, it is to be understood that the specific terminology is not intended to be restrictive or confining and that various rearrangements of parts and modifications of detail may be resorted to without departing from the scope or spirit of the invention as herein claimed.

I claim:

1. In combination with a door and frame, a

swinging supporting structure for said door, comprising a stanchion pivotally mounted within the door frame, supporting arms affixed upon said stanchion and pivotally mounted upon the top and bottom ends of the door remote a vertical edge thereof, a second arm pivotally mounted within said door frame and inter-geared with one of said supporting arms, a link pivotally connected to the second named arm and to said door, the pivotal connection between said link and the door being disposed in spaced relation with the pivotal connection between the door and said supporting arms, whereby the door is rotated upon the supporting arms as said supporting arms are swung in opening and closing the door.

15

2. A pivotal swinging mounting for a door, comprising a bar, a pair of arms affixed thereto and adapted to pivotally support a door, a second arm geared to one of the first named arms, and means associated with said second named arm to effect the rotation of the door upon the first named arms while said arms are swung in door opening and closing position.

3. A mounting for a swinging revolvable door, comprising an arm adapted to pivotally support a door, gear teeth on said arm, a trunnion pivotally supporting said arm, a second arm, gear teeth thereon, said teeth being inter-meshed with the gear teeth in the first named arm, and linkage connected with said second named arm and with the door to revolve said door within its opening when the door is secured in its opening or closing position.

4. In combination with a door, a swinging hinge mounting therefor comprising a pair of supporting arms mounted for swinging movement and pivotally connected to said door, gear teeth in one of said arms, a second arm, gear teeth thereon and intergeared with the teeth in said supporting arm, a link pivotally connected to said door and to said second named arm, said link being disposed to cause the rotation of said second named arm when the door is swung upon said supporting arms.

5. In combination with a door and door frame, a rotatable swinging mounting for said door, comprising a stanchion concealed within said frame and rotatably mounted thereon, a supporting arm affixed to said stanchion and pivotally connected to the upper end of said door, a gear toothed supporting arm affixed to said stanchion and pivotally connected to the lower end of said door, a third arm pivotally mounted in said frame, gear teeth therein, inter-geared with the second named arm, a link pivoted to said third named arm and to said door, the connection of said link with said door being disposed forwardly of the pivotal connection of said door with said supporting arms whereby the door will be rotated within its opening as it is swung there- 60 upon said supporting arms.

6. In combination with a door and door frame, a rotatable swinging mounting for said door comprising a rod concealed within said frame and rotatably mounted thereon, a supporting arm af- 65 fixed to said rod and pivotally connected to an end of said door adjacent an edge thereof, a gear toothed supporting arm affixed to said rod and pivotally connected to the opposed end of said door adjacent an edge thereof, a third arm piv- 70 otally mounted in said frame, gear teeth therein, intergeared with the second named arm, a link pivoted to said third named arm and to said door, the pivotal connection of said link with said door being disposed forwardly of the pivotal connec- 75

tion of said door with said supporting arms whereby the door will be rotated within its opening that is as it is swung therein upon said supporting arms.

- 5 7. In combination with a door and door frame, a rotatable swinging mounting for said door, comprising a stanchion concealed within said door frame and rotatably mounted thereon, a supporting arm affixed to said stanchion and pivotally connected to one end of said door, a gear toothed supporting arm affixed to said stanchion and pivotally connected to the other end of said door, an anti-friction bearing concealed in the marginal edge of said door constituting the pivotal connection of said gear toothed supporting arm, a third arm pivotally mounted in said frame, gear teeth therein, intermeshed with the second named arm, a link pivoted to said third named arm and to said door, the connection of said link with said door being disposed forwardly of the pivotal connection of said door with said supporting arms whereby the door will be rotated within its opening as it is swung therein upon said supporting arms.
- 10
- 15
- 20

8. In combination with a door having a cut-away portion in the marginal edge thereof and door frame, a rotatable swinging mounting for said door, comprising a stanchion concealed within said frame and rotatably mounted thereon, a supporting arm affixed to said stanchion and pivotally connected to one end of said door, a gear toothed supporting arm affixed to said stanchion and pivotally connected to the other end of said door, a third arm pivotally mounted in said frame, gear teeth therein, intergeared with the second named arm, a plate adjacent said second named arm the walls thereof defining a recess, a link pivoted to said third named arm, said link having an offset portion therein extended within said recess in said plate and being pivoted to said door within said recess, the pivotal connection of said link with said door being disposed forwardly of the pivotal connection of said door with said supporting arms whereby the door will be rotated within its opening as it is swung therein upon said supporting arms.
